UNITED STATES PATENT OFFICE

CONRAD R. SCHUMACHER, OF LYNBROOK, NEW YORK, ASSIGNOR, BY MESNE ASSIGNMENTS, TO GILLETTE SAFETY RAZOR COMPANY, OF BOSTON, MASSACHUSETTS, A CORPORATION OF DELAWARE

METAL SHARPENING MACHINE

Application filed April 30, 1928. Serial No. 273,835.

The object of my invention is to provide means for honing or grinding the edges of metal parts, and particularly the edges of metal strips which may be honed or ground while traveling through the machine.

The invention comprises a rotative member provided with surfaces to sharpen the metal and mounted to move against the metal under the influence of centrifugal force while the member rotates to cause the sharpening surfaces to engage the metal.

The invention also comprises novel details of improvement that will be more fully hereinafter set forth and then pointed out in the claims.

Reference is to be had to the accompanying drawings, in which,

Fig. 1 is a vertical cross section through the machine;

20 Fig. 2 is a section on line 2, 2, in Fig. 1;

Fig. 3 is a detail of one of the sharpening members;

Fig. 4 is a detail of a driving wheel for a sharpening member;

25 Fig. 5 is a cross section illustrating a modification;

Fig. 6 is a side view of a sharpening machine embodying the invention, and

30 Fig. 7 is a plan view of Fig. 6.

Similar numerals of reference indicate similar parts in the several figures.

The numeral 1 indicates a suitable support or frame shown provided with spaced uprights 2 having bearings at 3 in which a drive shaft 4 is journaled. The shaft 4 may be rotated by means of a pulley 5 thereon driven by a belt 6 operated by a pulley 6a on main drive shaft 6b to be rotated by any suitable source of power, or shaft 4 may be operated in any other desired way. At 7 are sharpening members loosely mounted upon shaft 4 to swing or rock laterally relatively to the plane of the axis of the shaft, under the influence of centrifugal force during rotation, to engage the edge portions of the metal 8 to be sharpened. In the example illustrated the shaft is provided with curved surfaces at 9, upon which the members 7 are mounted, said members having complementary curved surfaces at 10 engag-

ing the surfaces at 9, in the nature of a ball or universal joint, whereby the members 7 may swing or rock on shaft 4. The curved surfaces 9 are shown formed on projecting portions of sleeves 11 mounted on shaft 4 and secured thereto by pins 12. The members 7 are shown provided with peripheral projections or fingers 7a, suitably spaced apart, said fingers being provided with sharpening means at 13 to engage the metal 8. The sharpening means 13 may comprise suitable material, such as stones or the like for honing the metal, or grinding or abrading material for grinding the metal. The sharpening means 13 are shown located on the outer faces of the projections 7a so as to engage the side edges of the metal or strip 8 as indicated in Figs. 1 and 5.

In order to rotate the members 7 by and with the shaft 4, and permit said members to have swinging or rocking movements in a lateral direction, the shaft 4 is shown provided with a toothed wheel 14 located adjacent to and between the members 7, which wheel may be secured to the shaft by a pin 15, and said members are provided with laterally disposed projections or pins 16 adapted to enter between the teeth of wheel 14 for rotating the members by engagement of the teeth with the projections. The projections or pins 16 will operate freely between the teeth of wheel 14 during swinging or rocking movements of the members 7.

The metal strip or piece 8 may be supported in any desired way to be engaged by the sharpening means 13. In the example illustrated a guide bar 17 is shown provided with a longitudinal groove 17a in which the strip 8 is slidably guided, to retain the edge portion of the strip in position to be engaged by the sharpening means 13. The guide bar 17 is shown supported in slots 18a in uprights 18 on frame 1, the bar being opposed by adjusting screws 19 operative in said uprights, whereby the guide bar 17 may be adjusted vertically to place the edge of strip 8 in desired position to be sharpened. Screws 20 operative in the uprights 18 against the bar 17 serve to retain the latter in adjusted position.

The strip 8 may be supplied in any well known or desired way, such as a flexible strip wound on a reel 21, journaled on frame 1, and said strip may be fed with respect to 5 the rotating members 7 in any well known or desired way. I have illustrated feed rollers 22 bearing against the sides of the strip 8 to feed it, the rollers being carried by shafts 23 journaled on frame 1 and driven 10 by gearing 24, 25, 26, 27, operated by drive shaft 6b in a well known way.

The fingers 7a of one member are adapted to project through the spaces between the fingers of the other member 7, and portions 15 of the fingers of one member having the sharpening means 13 project beyond the fingers of the other member, so that the sharpening means of the members respectively bear against opposite side edges of 20 strip 8, Figs. 1 and 5. The members 7 are supported on opposite sides of a plane passing through the strip 8, and the strip is retained in a plane between the supporting means of the members, and when the strip is 25 between the crossed fingers of said members the latter are tilted. When the members 7 are axially rotated by and with shaft 4 centrifugal force will be set up in said members which will tend to cause them to rock to seek 30 a rectangular position respecting the axis of shaft 4, which tendency will be resisted by contact of the sharpening means 13 against the strip 8, hence said force will serve to press said means against the strip with a 35 pressure commensurate with the speed of rotation of members 7. During rotation of said members the strip 8 will be propelled, as in the direction of the arrow in Fig. 2, the fingers will intermesh as the members 40 rotate in unison, and the contact of the means 13 with the side edge portions of the strip will sharpen the latter.

As illustrated in Fig. 2 portions of the means 13 of several fingers of each member 45 7 will always be in contact with strip 8, and as the members 7 rotate equally and together and press simultaneously on opposite sides of the strip 8 one member will resist side pressure of the other member on the strip 50 and thus the members will tend to keep the sharpened edge of the strip in a straight line or without laterally deflecting the strip.

While two members 7, each having sharpening means 13, are illustrated, adapted 55 for simultaneously sharpening opposite side edges of the strip 13, it will be understood that a single member 7 may be used when it is desired only to sharpen one side edge of the strip. When two edge portions of a strip 60 are to be sharpened the members 7 may be arranged in spaced relation, as against the upper and lower edges of the strip as illustrated in Figs. 6 and 7. When a single edge portion of the strip is to be sharpened one 65 of the pair of members 7 may be omitted.

Any suitable means may be provided for severing the continuous sharpened strip 8 into desired lengths, such as for razor blades. Means for such purpose are indicated at 70 28 of a known variety, adapted to be operated from shaft 6b.

Having now described my invention what I claim is:—

1. A sharpening machine comprising a pair of separate spaced members located side 75 by side at an angle to one another and having sharpening means in opposing relation on side faces of the members, means supporting said members for common axial rotation and each member for individual angular rocking movement with respect one to another due to centrifugal force in said members during rotation thereof, means to rotate said members, and means to support a piece of metal in position between said members to be sharpened by said sharpening means with the axis of a member on the side of the metal remote from the side of the metal engaged by the sharpening means of 80 said member.

2. A sharpening machine comprising a pair of spaced individual members located side by side and having sharpening means in 85 opposing relation on side faces of said members, a shaft, means individually rockably supporting said members on a common axis upon said shaft for lateral angular movement relatively one to the other and to the axis of said shaft, means to rotate said members, and means to retain a piece of metal 90 between said members in position to be sharpened by said sharpening means with the axis of a member on the side of the metal remote from the side of the metal engaged by the sharpening means of 95 said member.

3. A sharpening machine comprising a pair of members having spaced peripheral fingers provided with sharpening means, a shaft, means rockably supporting said members upon the shaft to permit said members to have lateral rocking movements relatively to the axis of the shaft, means to rotate said members in unison with fingers of one member between fingers of the other member, and means to support a piece of 100 metal between sharpening means of said members whereby centrifugal force in said members due to their rotation will cause the sharpening means to bear against said metal during rotation of said members.

4. A sharpening machine as set forth in claim 3 in which the means rockably supporting the members upon the shaft includes spaced curved surfaces on the shaft and complementary curved surfaces on the members 105 respectively mounted upon the first named curved surfaces to permit the members to rock relatively to the axis of the shaft.

5. A sharpening machine comprising a pair of members having spaced peripheral 110

fingers provided with sharpening means on side faces of said members opposing metal to be sharpened, a shaft, means rockably supporting each of said members individually in spaced axial relation upon the shaft with fingers of one member projecting through the spaces between fingers of the other member, means to support a piece of metal in a plane between said member supporting means, the sharpening means on said fingers respectively engaging the said metal on the side of said plane opposite the support of the corresponding member on the shaft, and means to rotate the members 15 in unison.

6. A sharpening machine comprising a pair of members having spaced peripheral fingers provided with sharpening means on side faces of said members opposing metal to be sharpened, a shaft, means rockably supporting said members in spaced axial relation upon the shaft with fingers of one member projecting through the spaces between fingers of the other member, means to 20 support a piece of metal in a plane between said member supporting means, the sharpening means on said fingers respectively engaging opposite sides of the said metal, and means to rotate the members in unison including a toothed wheel on the shaft and 25 projections on the members engageable with the teeth of said wheel.
